Primary Examiner — Darlington Ly*Assistant Examiner* — Daniel J Domino(74) *Attorney, Agent, or Firm* — Mark Nowotarski(57) **CLAIM**

I claim, the ornamental design for a display screen portion with graphical user interface, as shown and described.

DESCRIPTION

The figure is a front view of a display screen portion with graphical user interface, showing my new design.

The outermost broken lines showing a portion of a display screen and the broken lines showing elements of the graphical user interface illustrate portions of the article, none of which form part of the claimed design.
